(57) **CLAIM**

The ornamental design for a energy consumption analyzing device, as shown and described.

DESCRIPTION

FIG. 1 is a front elevational view of the energy consumption analyzing device of the present invention;
FIG. 2 is a rear elevational view of the energy consumption analyzing device of FIG. 1;

FIG. 3 is a left side elevational view of the energy consumption analyzing device of FIG. 1, the right view being a mirror image thereof; and,

FIG. 4 is a top plan view of the energy consumption analyzing device of FIG. 1, the bottom view being a mirror image thereof.
